UNITED STATES PATENT OFFICE.

KEDILAN F. HAND AND FRANK T. CAVIN, OF LOS ANGELES, CALIFORNIA; SAID HAND
ASSIGNOR TO SAID CAVIN.

COTTON PICKER.

Application filed October 11, 1920. Serial No. 416,017.

To all whom it may concern:

Be it known that we, KEDILAN F. HAND and FRANK T. CAVIN, subject of Great Britain and citizen of the United States, respectively, both residing in Los Angeles, county of Los Angeles, State of California, have jointly invented new and useful Improvements in Cotton Pickers, of which the following is a specification.

This invention has to do with a cotton picker and it is an object of the invention to provide certain improvements in a device of this character to render it simple, compact, inexpensive to manufacture, and easy and convenient to operate.

In a general way the present invention relates to a cotton picker of the character set forth in our copending application entitled Cotton picker, filed April 5, 1920, Ser. No. 371,427. This particular invention, however, provides certain features and improvements over the device set forth in the above mentioned application making it practical and in a form to facilitate cotton picking at a very low cost.

A particular and noteworthy feature of the present invention is the manner in which the cotton is handled by the machine. In practice one sack or bag after another can be filled with cotton without interfering with the operation of the machine or without discontinuing picking and without loss of cotton at the times when the sacks or bags are being placed in or removed from the machine. The machine is actually constructed to simultaneously carry two bags and is provided with a control or distributing device by which the cotton may be directed into either of the bags. It will be understood of course how a full bag may be removed from the machine and replaced by an empty bag while the other bag is being filled. This feature of the invention greatly facilitates in making the machine effective and efficient and therefore of particular commercial value.

Another noteworthy feature of the invention is the provision of adjusting means in connection with the hose which are manipulated by the attendants. The hose may be adjusted to a level where they will be convenient for the attendants to handle and where they will function properly and effectively.

The various objects and features of the

invention will be best and more fully understood from the following detailed description of a specific preferred form of the invention throughout which reference is had to the accompanying drawings in which—

Fig. 1 is a side elevation of the improved device; Fig. 2 is a plan view thereof; Fig. 3 is an enlarged horizontal sectional view of the adjustable structure in connection with the hose, being a view taken as indicated by line 3—3 on Fig. 1; Fig. 4 is an enlarged vertical sectional view of the parts shown in Fig. 3 being a view taken as indicated by line 4—4 on Fig. 3; Fig. 5 is an enlarged plane section taken as indicated by line 5—5 on Fig. 1, being a view showing the distributing device, and Fig. 6 is an enlarged detailed sectional view through the fan, being a view taken as indicated by line 6—6 on Fig. 1.

Throughout the drawings numeral 10 designates the frame of the machine which is supported at its forward end by traction wheels 11 and at its rear end by wheels 13. The wheels 13 are carried on a shaft 17 secured to the frame 10 by arms 18. The arms 18 are vertically and horizontally adjustably connected to the frame 10 by clamps 19. The clamps 19 grip upwardly extending portions 18^a of arms 18 and a horizontal part 10^a of frame 10. This construction permits the height of the handle 14^a and the spacing of the wheels 13 to be varied as desired. The handle 14 comprises a member 14^a which extends upwardly and rearwardly from the frame 10, and a cross bar 14^b mounted on the rear end of the member 14^a. The cross bar 14^b is formed at its ends with hand grips adapted to form convenient handles for the operator to grip when steering and handling the machine.

The wheels 11 are mounted on a shaft 16 which forms the crank shaft of the engine 16^a. The wheels are loosely mounted on shaft 16 and are adapted to be driven through clutch mechanisms 16^b. Each clutch mechanism is provided with a control rod 16^c which extends to the cross bar 14^b of the handle. With this construction the engine can be operated continuously and the machine advanced or moved when desired by suitable operation of clutches 16^b. It will be obvious how the machine can be very easily turned by operation of the clutches to cause one wheel to rotate faster

than the other. The particular construction herein so far described is more or less common to light tractors and is intended merely to illustrate a form of machine or apparatus which may be advantageously used in carrying out the present invention.

A fan or blower 20 is mounted at the forward end of the frame 10. The intake or suction pipe 21 of the blower 20 extends vertically upwardly, in the manner clearly shown in Fig. 1 and has a plurality of flexible conduits or hose connected into it at its upper end. The hose 22 are adapted to be operated or manipulated by attendants in the manner hereinafter described. These hose 22 may be rubber or flexible metallic hose and may be of various lengths to suit the particular circumstances under which the machine is to be operated. In the particular construction shown in the drawings two hose connect into the front of the suction pipe and one hose connects into each side of the suction pipe. The hose 22 which connect into the sides of the suction pipe may be supported by a horizontal cross arm 24.

The suction pipe 21 is adjustable or extensible being formed of two sections 25 and 25^a one slidably within the other. The section 25^a is the lowermost and is connected directly to the blower 20, while the section 25 is uppermost and is adapted to slidably fit within the lower section 25^a. The fitting of the upper section into the lower one prevents cotton being caught at the joint between the two sections as it passes downwardly to the fan. The joint between the two sections 25 and 25^a is sealed by a band 27, preferably leather, or the like, which is arranged around it in the manner shown in Fig. 4. A split clamping ring 28 is arranged around the band 27 and is formed with flanges 23 which carry bolts 29. The bolts 29 may be tightened so that the two sections 25 and 25^a are solidly held or clamped against relative movement or they may be tightened so that the two sections may be moved or adjusted by hand. In practice it may be found desirable to adjust the suction pipe to the proper height for the particular circumstances under which the machine is to operate and then solidly and securely clamp it in that position. It will be understood how the suction pipe may be adjusted to a height where the cotton will be drawn through the hose 22 in the most effective manner and with the least amount of resistance. The details of the connection between the sections 25 and 25^a are clearly shown in Figs. 3 and 4 of the drawings. It will be noted in the drawings that the upper part of the band 27 is considerably thicker than the lower part thus permitting of the split ring being of uniform diameter and

yet causing the section 25 and the section 25^a to be gripped uniformly when the clamping bolts 29 are tightened. This particular portion of the machine is believed to be particularly noteworthy in that it provides a novel, simple means for adjusting the length of the suction pipe and thereby adjusting the hose to the most desirable and advantageous height. The particular construction at this part of the machine is noteworthy in that it provides a conveniently adjustable structure which is simple and inexpensive to manufacture and which does not interfere with the operation of the machine in any way.

The blower 20 comprises generally a suitable casing into which extends a shaft 40. A plurality of paddles 39 are carried within the casing on arms 38 which extend from a hub 38^a mounted on the shaft 40. In the preferred form of construction a disk 38^b is carried on the shaft 40 in the manner shown in Fig. 6 to support or brace the paddles 39. In the particular form of construction herein set forth the casing comprises a central member 42 which extends around the paddles 39 and is secured or carried between two plates 44. The member 42 and plates 44 may be advantageously connected by angle irons 43 in the manner clearly shown in Fig. 6. A bracket or casting 45 is bolted to one of the plates 44 and is formed with a bearing 45^a in which is carried the shaft 40, and is formed with a foot 48 adapted to be bolted to the frame 10. A bracket or casting 46 is bolted to the other plate 44 and is formed with a neck part 47 which carries the section 25^a of the suction pipe and connects the section 25^a with the interior of the fan casing, and is formed with a foot 49 adapted to be bolted to the frame 10. The fan is driven from shaft 16 by a belt 50 carried on pulleys 51^a and 52 mounted on shafts 16 and 40 respectively. The shaft 16 being a constantly operating member the fan is operated at all times even when the machine is not being moved. It will be readily understood how the particular arrangement and construction just set forth is simple and inexpensive and how it permits of the fan being easily and quickly taken apart for cleaning, etc.

The discharge pipe 54 of the fan is connected with a V-shaped, or forked, distributing pipe 56 by a flexible pipe 55. The distributing pipe is mounted on the upwardly and rearwardly extending member 14^a of the handle 14 to be near the cross bar 14^b and to have one of its side portions 57 on each side of the member 14^a, as clearly shown in the drawings. The outer end portion of each side portion preferably turns downwardly so that the cotton will be discharged downwardly. A valve 58 is arranged in the distributing pipe at the junction of the side

portions 57. The valve is carried on a stem 60 which has an operating lever 61 mounted on it at the exterior of the pipe. From inspection of the drawings, particularly of Fig. 5 of the drawings, it will be understood how the valve can be operated to close off either one of the side portions and cause all of the cotton to discharge through the other side portion, and how it can be operated to allow both of the side portions to be open so that the cotton will discharge through both of them. When the valve is thrown to either side, that is so as to close either one of the side portions, it will remain in that position until positively operated or moved by the lever 61.

Two bags 65 are carried by the handle 14 to receive the cotton from the distributing pipe 56. Each bag is carried by hooks 66, mounted on the member 14^a and cross arm 14^b, so that its top is open and so the one of the side portions 57 extends slightly into it. The bags being carried by the hooks can be easily arranged in place and removed from the machine.

In the preferred form of construction a guard or shield 80 is arranged around the machine so that it can be passed between the rows of cotton plants without injuring or catching them.

In the operation of machine the engine 16^a is constantly operated causing the fan to be constantly operated and permitting of the machine being moved whenever desired. The outer end of each hose is placed by an attendant at or near ripe bolls of cotton so that the cotton is drawn into the hose by the sucking action of the fan. It will be understood how the cotton from the several hose enters the suction pipe 21, passes through the fan, passes through the discharge pipe 54 and the conduct 55, and finally through the distributing pipe 56 from whence it is discharged into the bags 65. An operator manipulates the clutch mechanisms to move

the machine as the cotton is gathered, and removes the bags from the hooks as they are filled and replaces them by the empty ones. It is obvious how the operator can manipulate the valve 58 so that one bag is being filled while a full bag is being removed and an empty one put in its place. This manner of operation is continuous and makes for quick efficient picking of cotton. When a machine is constructed with four hose as shown in the drawings two rows of cotton can be picked at a time. Two attendants can pass between the rows of cotton between which the machine is moved and can each pick the cotton on the inner side of one of the rows. Two other attendants can pass along the outer side of the rows and can each pick the cotton on the outer side of one of the rows.

We claim—

In a cotton picking machine of the character described, supporting wheels, power means supported by the wheels, a releasable driving connection between the power means and supporting wheels, a blower, a driving connection between the power means and the blower, a hose in connection with the intake of the blower, a handle in connection with the parts supported by the wheels by which the machine may be guided, control means for the first mentioned driving connection and extending to the handle so that said driving connection can be controlled by a person operating the handle, a conduit in connection with the discharge of the blower and extending to the handle, and a bag detachably carried at the handle to receive cotton from said conduit.

In witness that we claim the foregoing we have hereunto subscribed our names this 30th day of September, 1920.

KEDILAN F. HAND.
FRANK T. CAVIN.
